UNITED STATES PATENT OFFICE

ADOLPH GRAMLICH, OF BRONX, NEW YORK

DESIGN FOR A DOLL OR SIMILAR ARTICLE

Application filed March 22, 1929. Serial No. 30,586. Term of patent 14 years.

To all whom it may concern:

Be it known that I, ADOLPH GRAMLICH, a citizen of the United States, and a resident of the United States, residing in the borough of the Bronx and the State of New York, whose post-office address is 362 E. 164th St., New York, N. Y., have invented a new, original, and ornamental Design for a Doll or Similar Article, of which the following is a specification, reference being had to the accompanying drawings, forming a part thereof.

Fig. 1 is a front elevational view of a doll or similar article, showing my new design; and Fig. 2 is a side view of the same on a reduced scale.

I claim:

The ornamental design for a doll or similar article, as shown.

ADOLPH GRAMLICH.
